[57] CLAIM

The ornamental design for a brake arch adapter for bicycle suspension fork, as shown and described.

DESCRIPTION

FIG. 1 is a perspective view of the first embodiment brake arch adapter for bicycle suspension fork, showing my new design;

FIG. 2 is a front elevational view;

FIG. 3 is a rear elevational view;

FIG. 4 is a top plan view;

FIG. 5 is a bottom plan view;

FIG. 6 is a left side elevational view when viewed from the front;

FIG. 7 is a right side elevational view when viewed from the front;

FIG. 8 is a perspective view of a second embodiment of the brake arch adapter for bicycle suspension fork, showing my new design;

FIG. 9 is a front elevational view of FIG. 8;

FIG. 10 is a rear elevational view of FIG. 8;

FIG. 11 is a top plan view of FIG. 8;

FIG. 12 is a bottom plan view of FIG. 8;

FIG. 13 is a left side elevational view of FIG. 8 when viewed from the front; and,

FIG. 14 is a right side elevational view of FIG. 8 when viewed from the front.
